UNITED STATES PATENT OFFICE.

DEL ROY LANGSTAFF, OF LOS ANGELES, CALIFORNIA.

NON-REFILLABLE BOTTLE.

1,172,218.

Specification of Letters Patent. Patented Feb. 15, 1916.

Application filed May 26, 1914. Serial No. 841,018.

To all whom it may concern:

Be it known that I, DEL ROY LANGSTAFF, a citizen of the United States, residing at Los Angeles, in the county of Los Angeles, State of California, have invented new and useful Improvements in Non-Refillable Bottles, of which the following is a specification.

This invention relates to a non-refillable bottle.

It is the object of this invention to provide a non-refillable bottle in which the use of springs, ball valves and metallic parts are dispensed with, and which comprises few elements which may be readily manufactured and assembled and mounted in a bottle neck to effectively prevent the introduction of a liquid into the bottle through the neck thereof, but which will readily permit its contents being discharged therefrom.

A further object is to provide an attachment for bottle necks for preventing the introduction of liquids therethrough and which is so constructed that it can not be rendered inoperative by the introduction of wires or the like.

The invention is illustrated in the accompanying drawings, in which:

Figure 1 is a view in vertical section of a bottle neck, showing the invention as applied, and illustrating the device in side elevation. Fig. 2 is a vertical section on the line 2-2 of Fig. 1, as seen in the direction indicated by the arrows, and showing the valve in its closed position. Fig. 3 is a detail in section showing the manner in which the valve opens to permit the discharge of the contents of the bottle. Fig. 4 is a horizontal section on the line 4-4 of Fig. 2. Fig. 5 is a horizontal section on the line 5-5 of Fig. 2.

More specifically, 6 indicates a cylindrical body member preferably formed of glass and which is adapted to be rigidly mounted in a bottle neck 7 in any desired manner after the bottle has been filled. The body member 6 is formed with a recess 8 on one side thereof, the upper end of which communicates through a channel 9 formed on the outer periphery of the body member 6 with the lower end of a curved passage 10, the upper end of which opens at the upper end of the body member 6 to form a discharge opening 11. A depending lip 12 is formed on the body member 6 on the top

wall of the recess 8; the inner face of which lip is spaced from the rear wall of the recess 8 and forms a shoulder or stop to limit the pivotal movement of a vertically disposed flat plate 13, the lower end of which is pivotally mounted in the lower end wall of the recess 8, as will presently be described.

The upper portion of the rear wall of the recess 8 is formed with a ground face 14 and the rear face of the plate 13 is ground to conform thereto so that when the plate 13 is against the face 14 a close contact will be effected. Formed in the ground face 14 rearward of the plate 13 is an opening 15 communicating with a passage 16 leading downwardly and opening to the underside of the body member 6 to the interior of the bottle neck 7. Formed in the body member 6 beneath the lower end wall of the recess 8 is an opening 17 which extends through the body member 6 and communicates with the recess 8 through a slot 18. The lower portion of the rear wall of the recess 8 is off-set as indicated at 19 to form a clearance rearward of the lower portion of the vertical plate 13 and also to form a rib 20 on the inner marginal edge of the slot 18 against which rib the rear face of the plate 13 abuts. The forward edge of the slot 18 projects into a transverse groove 22 formed on the plate 13 and coacts with the rib 20 to form a pivotal mounting for the plate. The front and rear marginal edges of the slot 18 contact the lower end of the plate 13 on the opposite sides thereof in such manner as to normally maintain this plate in a vertical position as shown in Fig. 2.

In assembling the device the plate 13 is introduced sidewise into the slot 18 and positioned as shown in Fig. 5, whereupon the material of which the body member 6 is formed is turned inwardly at the ends of the slot 18 to lock the plate 13 in place. The body member 6 is then mounted in the bottle neck 7 in any desired manner after the bottle is filled, with its upper end disposed a suitable distance below the top of the bottle neck to permit the use of an ordinary cork 23.

In the operation of the invention, when it is desired to pour the contents from the bottle it is tipped to the position shown in Fig. 3, whereupon the liquid in passing

through the passage 16 will force the plate 13 away from the opening 15, thus allowing the liquid to flow around the edges of the plate 13 in the recess 8 from whence it passes through a channel 9 into the curved passage 10, from whence it is discharged through the end opening 11. The lip 12 then serves as a stop to limit the movement of the plate 13. When the bottle is restored to its vertical position the plate 13 will be turned back against the ground face 14 to effectively close the opening 15. When in this position liquid can not be introduced into the bottle through its upper end, as such liquid as may be introduced through the passage 10 into the recess 8 will serve to hold the plate 13 in its closed position. The lip 12 in projecting below the upper end of the plate 13 guards the latter from being unseated by the introduction of a wire or other instrument through the curved passage 10 which by reason of its curvature also renders it difficult to insert a wire therethrough.

From the foregoing it will be seen that I have provided an attachment for bottle necks where easy refilling of the bottle is prevented and which device can be made of glass or porcelain or other non-corrosive material and which is free from the objections common to the use of springs and ball valves.

What I claim is:

1. An attachment for bottle necks, comprising a body member adapted to be mounted in the neck of a bottle having a recess on its peripheral side wall, a discharge passage connecting with said recess and opening at the upper end of the body member and having a passage leading from the underside of the body member to the vertical wall of the recess, and a plate pivoted in the lower wall of the recess normally abutting against the rear wall of the recess

to close the upper end of the last-named passage.

2. An attachment for bottle necks, comprising a body member adapted to be mounted in the neck of a bottle having a recess on its peripheral side wall, a discharge passage connecting with said recess and opening at the upper end of the body member and having a passage leading from the underside of the body member to the vertical wall of the recess, and a tiltable plate pivoted in the lower wall of the recess normally abutting against the rear wall of the recess to close the upper end of the last-named passage, and a depending lip on said body member projecting below the upper edge of said pivoted plate to limit the movement of the latter.

3. In a non-refillable bottle, comprising the combination with a bottle neck, of a body member adapted to be mounted in the bottle neck having a recess on one side thereof and formed with an opening extending therethrough beneath the recess and communicating with the recess through a slot, a depending lip on the upper wall of the recess on the outer face of which is formed a channel which connects at one end to the recess and at the opposite end to a curved passage in the body member, and a plate in said recess having its lower end pivotally engaged in the slot and its upper end projecting rearwardly of the lip, said plate normally closing an opening which communicates with the interior of the bottle neck below the body member.

In witness that I claim the foregoing I have hereunto subscribed my name this 16th day of May, 1914.

DEL ROY LANGSTAFF.
